US00D864474S

(12) **United States Design Patent** (10) **Patent No.:** **US D864,474 S**
(45) **Date of Patent:** **** Oct. 22, 2019**

(54) **VAPORIZER DEVICE**

- (71) Applicant: **Cortney Smith**, Las Vegas, NV (US)
(72) Inventor: **Cortney Smith**, Las Vegas, NV (US)
(**) Term: **15 Years**
(21) Appl. No.: **29/644,286**
(22) Filed: **Apr. 16, 2018**

Related U.S. Application Data

- (63) Continuation-in-part of application No. 29/600,786, filed on Apr. 14, 2017, and a continuation-in-part of application No. 29/600,775, filed on Apr. 14, 2017, now Pat. No. Des. 851,328, which is a continuation-in-part of application No. 29/579,220, filed on Sep. 28, 2016, now Pat. No. Des. 806,311, which is a continuation-in-part of application No. 29/579,220, filed on Sep. 28, 2016, now Pat. No. Des. 806,311.

CLAIM

The ornamental design for a vaporizer device with surface ornamentation, as shown and described.

DESCRIPTION

FIG. 1 is a front right top perspective view of a vaporizer device showing my new design;
FIG. 2 is a back right top perspective view thereof;
FIG. 3 is a front view thereof;
FIG. 4 is a back view thereof;
FIG. 5 is a top view thereof;
FIG. 6 is a bottom view thereof;
FIG. 7 is a left side view thereof;
FIG. 8 is an opposite side view thereof;
FIG. 9 is a back left top perspective view thereof;
FIG. 10 is a front left top perspective view thereof;
FIG. 11 is a front right bottom perspective view thereof;
FIG. 12 is a back right bottom perspective view thereof;
FIG. 13 is a back left bottom perspective view thereof; and,
FIG. 14 is a front left bottom perspective view thereof.
In FIGS. 1, 3, 7-8, 10-11, and 14, the array of circles is a surface ornamentation applied to the vaporizer device.
In FIGS. 6, 11, and 14, the dash-dash broken line structures depict portions of the vaporizer device that form no part of the claimed design. In FIGS. 1-2 and 9-14, the dot-dash broken lines define the bounds of the claimed design and form no part thereof.

1 Claim, 6 Drawing Sheets
